ELECTRIC CIGARETTE LIGHTER CHARGER AND
STORAGE DEVICE OR SIMILAR ARTICLE

Olle E. Haggstrom, Trumbull, Carl N. Johnson, Strat-
ford, and William V. Judson, Westport, Conn., assign-
ors to General Electric Company, a corporation of New
York

Filed June 14, 1965, Ser. No. 85,709

Term of patent 14 years

(Cl. D26—15)

Fig. 1.

Fig. 3

Fig. 2.

Fig. 4.

Fig. 5.

Fig. 6.

FIG. 1 is a front perspective view of an electric cigarette lighter charger and storage device embodying our new design;

FIG. 2 is a top plan view of the electric cigarette lighter charger and storage device shown in FIG. 1;

FIG. 3 is a rear elevational view of the electric cigarette lighter and storage device shown in FIG. 1;

FIG. 4 is a front elevational view of the electric cigarette lighter and storage device shown in FIG. 1;

FIG. 5 is a side elevational view of the electric cigarette lighter and storage device shown in FIG. 1 the opposite side being substantially a mirror image thereof; and

FIG. 6 is a bottom plan view of the electric cigarette lighter and storage device shown in FIG. 1.

Portions of the drawing figures are stippled to indicate contrast in appearance.

We claim:

The ornamental design for an electric cigarette lighter charger and storage device or similar article, substantially as shown and described.
